DESIGN FOR A STOCKING

Janet May, New York, N. Y.

Application April 9, 1938, Serial No. 76,403

Term of patent 7 years

To all whom it may concern:

Be it known that I, Janet May, a citizen of the United States, residing at New York city, in the county and State of New York, have invented a new, original, and ornamental Design for a Stocking, of which the following is a specification; reference being had to the accompanying drawing, forming a part thereof.

This application is a continuation in part of my application Serial No. D-74,767, filed January 31, 1938.

The figure is a perspective view of a stocking, showing my new design.

The characteristic feature of the design resides in the ornamental border surrounding the open toe portion of the stocking, substantially as shown.

I claim:

The ornamental design for a stocking, substantially as shown and described.

JANET MAY.
